CAN OPENING DEVICE

John Yogi Izumi, Chicago, Ill.

Application August 14, 1950, Serial No. 179,216

10 Claims. (Cl. 30—8)

1

The invention relates generally to a can opening device and more particularly to a device of the character in which a pouring opening is punched in the can.

A general object of the invention is to provide a new and improved can opening device that operates with ease and facility, and is sturdy and trouble-free.

A more particular object is to provide a can opening device that can be operated by one hand while the can is held in the hand.

Another object is to provide a can opening device adapted to be stationarily mounted and is operable by mere placing of a can in position against the device and swinging the can about an edge thereof.

Still another object is to provide a can opening device in which the can to be opened is employed as a lever for actuating the can punching mechanism.

A further object is to provide a can opening device in which the can punching mechanism is at the end of the punching operation automatically withdrawn from the can to free the same for ready disengagement from the device.

Other objects and advantages will become apparent from the following detailed description taken in connection with the accompanying drawings, in which:

Fig. 1 is a side elevational view of a can opening device embodying the features of this invention.

Fig. 2 is an enlarged longitudinal sectional view of the device of Fig. 1.

Fig. 3 is a longitudinal sectional view but showing the parts of the device in the position assumed just an instant before completion of the can punching operation.

Fig. 4 is a transverse sectional view taken approximately along the line 4—4 of Fig. 3.

Fig. 5 is a top plan view of the can opening device.

While the invention is susceptible of various modifications and alternative constructions, it is shown in the drawings and will hereinafter be described in a preferred embodiment. It is not intended, however, that the invention is to be limited thereby to the specific construction disclosed. On the contrary, it is intended to cover all modifications and alternative constructions falling within the spirit and scope of the invention as defined in the appended claims.

The can opening device disclosed herein is intended to be supported in a stationary position as on a wall and is adapted to perform its can

2

puncturing function simply by placing a can in the proper relationship to the device and then swinging the can forwardly and upwardly in a generally arcuate motion while it is partially suspended from the device. This is accomplished while the can is grasped and held in a hand of the operator, the can itself serving as the lever through which the force is applied and requiring no additional manipulation of parts. After an opening has been formed in the can as an incident to this simple forward and upward movement, the can punching element is withdrawn leaving the can free to be removed without the complication of having such an element projecting into the can. Upon removal of the can the mechanisms of the can opening device return automatically to the position for acting upon the next can to be opened.

For accomplishment of the above operations, 20 the device comprises generally an elongated frame or housing 10, a can positioning and guiding means, generally designated 11, mounted on said frame, a can punching element, generally designated 12, and controlling or triggering means 13 for the can punching element 12. More particularly, the frame 10 is elongated and is composed of a pair of side plates 14 and a pair of end plates or blocks 15, the side and end plates being secured together by screws or rivets 16. 25 The frame is adapted to be mounted in horizontal position on some stationary support, indicated at 17, in any conventional manner. Preferably the end opposite the controlling or triggering means 13 is the end that is attached to the stationary support and for convenience that end will be referred to as the forward end. Conceivably the frame could be attached to the supporting means at the opposite end. This, however, would make the operation of the device less convenient for the operator would be required to pull the can toward him rather than pushing it away from him, the latter being a more convenient gesture, and conceivably the can opening device need not be mounted at all but could with less convenience and with additional manipulations be employed as a portable opener applied to the can rather than having the can applied to it.

The can positioning and guiding means 11 is pivotally mounted near one of its ends and intermediate the ends of the frame 10 to swing about a horizontal axis or pivot. Herein the pivot is formed by a shaft 18 extending through the positioning and guiding member 11 and also through the side plates 14 of the frame. The shaft 18, 50 as will presently be made known, also serves a

second function, namely, that of a limit stop. The positioning and guiding means 11 is composed of a pair of plates 19 spaced apart laterally with a block 20 mounted between the plates at the free end. This block is weighted so as to tend to swing the means 11 downwardly to the position shown in Fig. 1. At the opposite ends the plates 19 are each formed with a hook 21 for engaging the top seam 22 of a can 23 placed with the top of the can against the under surface or side of the can positioning and guiding means 11.

The can punching element 12 is mounted to perform its can puncturing function as an incident to the swinging of the can and the can guiding and positioning means 11 from the position normally occupied by the means, as shown in Figs. 1 and 2, in a counterclockwise direction, as viewed in Figs. 1 to 3. With the device mounted at its right-hand end as here shown, this swinging movement of the guiding means 11 is accomplished by a convenient forward and upward pushing of the can 23, which is a convenient movement as well as one enabling considerable force to be applied. The punching element, moreover, is so mounted as to be automatically withdrawn from the can after it has performed its puncturing operation so as to free the can for convenient and ready disengagement from the guiding means, particularly the hooks 21 thereof. Herein the punching element 12 is caused to perform its various functions by being pivotally mounted on the can positioning and guiding member or means 11 eccentrically of the pivot of the means, that is, of the shaft 18. To that end a pin 24 extends between the plates 19 of the means 11, and the element 12 is pivoted thereon to lie between the plates. With respect to a generally longitudinal center line of the means 11, the pin 24 is positioned slightly rearwardly and downwardly of the shaft 18. As a consequence the pin 24 and the punching element 12 have a forward and a downward movement relative to the frame 10 as the can positioning and guiding means 11 is swung from its normal position, shown in Fig. 2, to its actuated position, shown in Fig. 3. This movement is utilized as will presently be made known in the control of the puncturing element.

The portion or end 25 of the punching element 12 extending forwardly of its pivot pin 24 is generally triangular in shape, as best seen in Fig. 4, terminates in a sharp point 26, and has its margins sharpened to form a piercing end. The portion 27 extending rearwardly from the pivot pin 24 serves as the actuating end for the punching element and to that end is generally rectangular. A spring 28 carried by a pin 29 extending between the plates 19 bears at its free end against the actuating end 27 of the punching element and thus tends to rotate the element in a counterclockwise direction, as viewed in Fig. 3, until the piercing end 25 strikes the shaft 18 at a time when the piercing end 25 lies approximately in the plane of the positioning and guiding means 11 and in position so that the point 26 lies just above the top of a can placed in position against the guiding means. A pin 30 extending between the plates 19 constitutes a second limit stop and determines the normal position of the various parts, particularly the can positioning and guiding means. This pin 30 is adapted to be engaged by the actuating end 27 of the punching element and the shaft 18 serves to limit the downward swing of the positioning

and guiding means to the oblique position shown approximately in Figs. 1 and 2.

Controlling or triggering the operation of the punching element 12 is the means 13 taking the form of an L-shaped dog pivotally mounted on a pin 31 at the rear of the frame 10. The dog tends to assume the position shown in Fig. 2, in which an operative leg 32 thereof projects forwardly into the path of the actuating end 27 of the punching element 12 and in that position is held against further rotation. The leg 32, however, is short enough so that the obliquely forward movement of the punching element incident to the swinging of the can positioning and guiding means is sufficient to move the actuating end 27 off of the leg 32 to free the punching element for rotation under the influence of the spring 28. Free and unrestricted return movement of the actuating end 27 is permitted by the pivoting of the triggering means 13.

As an aid in the understanding of the invention, particularly the functioning of the various elements, the positions and movements thereof will be described as an incident to a can puncturing operation. Let it be assumed, therefore, that the various mechanisms are in their normal positions, that is, with the actuating end 27 of the punching element against the stop 30 and with the means 11 therefor extending obliquely downwardly and forwardly. The piercing end 25 of the punching element will occupy what might be termed a retracted position relative to the can positioning and guiding means, as shown in Figs. 1 and 2, and the triggering means or dog 13 will be in its normal position, as shown in Fig. 2. To open a can it is simply grasped in one hand, one edge engaged on the hooks 21, and the can then swung forwardly toward vertical position of the can. As a result, the positioning and guiding means swings about its pivot shaft 18, that is, it pivots relative to the supporting frame 10. While the means 11 is free to pivot, the punching element 12 is not for its actuating end 27 is held against pivotal movement by the triggering means 13. As a consequence, there is relative pivotal movement between the means 11 and the punching element 12, and the piercing end 25 of the punching element is forced into the can shearing a triangular segment 33 from the top of the can and bending the same downwardly inside the can, as shown in Fig. 3.

Due to the eccentric mounting of the punching element 12 relative to the pivot shaft 18 of the can positioning and guiding means, the punching element, as already described, also has an obliquely downward and forward movement causing the actuating end 27 of the element to be withdrawn from the dog 13 after the segment 33 of the can top has been well bent into the can and prior to the time that the can strikes the bottom edge of the side plates 14. With the punching element now free the spring 28 rotates the same in a counterclockwise direction thereby withdrawing the piercing end 25 out of the can, and the latter is then free without any obstructions whatsoever to be disengaged from the hooks 21. Upon removal of the can the weighted block 20 swings the can positioning and guiding means back to its normal, oblique position in a clockwise direction carrying the punching element 12 with it. As the actuating end 27 of the element strikes the dog 13, it pivots to permit the end 27 to pass by and come to rest against the pin 30. The dog 13 swings back to its normal position where the leg 32 is in the path of the actuating end 27 of

the punching element and the device is again in condition for the next can opening operation.

It is believed apparent from the foregoing that I have perfected an efficient can opening device in which the device itself need not be touched and only one hand is required for the can opening operation.

I claim as my invention:

1. A can opening device comprising, in combination, an elongated frame adapted to be stationarily mounted in horizontal position, a can positioning and guiding member pivotally mounted near one of its ends in said frame and normally hanging downwardly, a can punching element pivotally mounted on said member eccentrically of the pivot of said member, said element having a piercing end extending generally in the direction of said member and an actuating end extending generally in the opposite direction, means urging said element in a direction tending to bring the piercing end of said element generally in the plane of said member, a stop carried by said member limiting movement of said element in the aforesaid direction when the piercing end of said element lies generally in the plane of said member, a stop carried by said frame adapted to be engaged by the actuating end of said element limiting pivotal movement of said element relative to said frame in a direction counter to the aforesaid direction and positioned to hold said member and said element in an obliquely downward position, and an abutment engaged by the actuating end of said element holding said element against rotation and forcing the piercing end thereof into a can held against the under face of said member and pushed upwardly in an arcuate path.

2. A can opening device comprising, in combination, an elongated frame adapted to be stationarily mounted in horizontal position, a can positioning and guiding member pivotally mounted near one of its ends in said frame and normally hanging downwardly, a can punching element pivotally mounted on said member, said element having a piercing end extending generally in the direction of said member and an actuating end extending generally in the opposite direction, means urging said element in a direction tending to bring the piercing end of said element generally in the plane of said member, a stop carried by said member limiting movement of said element in the aforesaid direction when the piercing end of said element lies generally in the plane of said member, a stop carried by said frame adapted to be engaged by the actuating end of said element limiting pivotal movement of said element relative to said frame in a direction counter to the aforesaid direction and positioned to hold said member and said element in an obliquely downward position, and an abutment engaged by the actuating end of said element holding said element against rotation and forcing the piercing end thereof into a can held against the under face of said member and pushed upwardly in an arcuate path, said element being pivoted downwardly and rearwardly of said member pivot to have a generally forward movement as said member is pivoted releasing said element from said abutment near the end of the swing of said member to free said element for retraction of its piercing end from the can.

3. A can opening device comprising, in combination, an elongated frame adapted to be stationarily mounted in horizontal position, a can positioning and guiding member pivotally

mounted near one of its ends in said frame and normally hanging downwardly, a can punching element pivotally mounted on said member, said element having a piercing end extending generally in the direction of said member and an actuating end extending generally in the opposite direction, means urging said element in a direction tending to bring the piercing end of said element generally in the plane of said member, a stop carried by said member limiting movement of said element in the aforesaid direction when the piercing end of said element lies generally in the plane of said member, a stop carried by said frame adapted to be engaged by the actuating end of said element limiting pivotal movement of said element relative to said frame in a direction counter to the aforesaid direction and positioned to hold said member and said element in an obliquely downward position, and an abutment engaged by the actuating end of said element holding said element against rotation and forcing the piercing end thereof into a can held against the under face of said member and pushed inwardly in an arcuate path, said element being pivoted downwardly and rearwardly of said member pivot to have a generally forward movement as said member is pivoted releasing said element from said abutment near the end of the swing of said member to free said element for retraction of its piercing end from the can, said abutment being pivotally mounted to permit return of said member and said element to their obliquely downward positions.

4. A can opening device comprising, in combination, a frame, a can positioning and guiding member pivotally mounted on said frame, a can punching element pivotally mounted on said positioning and guiding member and having a piercing end positioned to contact a can placed in position against said member, and means for holding said punching element against rotation relative to said frame while said positioning and guiding member is swung about its pivotal mounting to force the piercing end of said punching element into the can.

5. A can opening device comprising, in combination, a frame, a can positioning and guiding member pivotally mounted near one of its ends in said frame, said member at its pivoted end having a hook for engaging the bead on an edge of the can, a can punching element pivotally mounted on said positioning and guiding member at its pivoted end eccentrically of the pivot of said member, said punching element having a piercing end positioned to contact a can placed in position against said member, and an abutment on said frame engaged by said punching element for holding the same against rotation relative to said frame during the initial pivoting of said positioning and guiding member.

6. A can opening device comprising, in combination, a frame, a can positioning and guiding member pivotally mounted near one of its ends in said frame, said member at its pivoted end having a hook for engaging the bead on an edge of the can, a can punching element mounted for pivotal movement relative to said frame and said member and for longitudinal movement relative to said frame, a connection between said member and said punching element to move said element generally longitudinally as said member is pivoted, and an abutment on said frame engaged by said punching element during the major portion of the rotation of said member to hold said

piercing element against rotation relative to the frame.

7. A can opening device comprising, in combination, a frame adapted to be mounted on a stationary member, a can positioning and guiding member pivotally mounted near one of its ends in said frame, said member at its pivoted end having projecting means for engaging a can to aid in holding the same against said member, a can punching element mounted on said member at its pivoted end having a piercing end normally extending in the direction of and lying approximately in the plane of said member, and an abutment on said frame, engaged by said element when in normal position, holding said element against rotation relative to said frame, said punching element being pivotally mounted on said member eccentrically of the pivot of said member to have a limited generally longitudinal movement, as an incident to pivoting of said member, forcing it from said abutment.

8. A can opening device comprising, in combination, a frame adapted to be mounted on a stationary member, a can positioning and guiding member pivotally mounted near one of its ends in said frame, said member at its pivoted end having projecting means for engaging a can to aid in holding the same against said member, a can punching element mounted on said member at its pivoted end having a piercing end normally extending in the direction of and lying approximately in the plane of said member, an abutment on said frame, engaged by said element when in normal position, holding said element against rotation relative to said frame, said punching element being pivotally mounted on said member eccentrically of the pivot of said member to have a limited generally longitudinal movement, as an incident to pivoting of said member, forcing it from said abutment, and means urging said punching element to its normal position.

9. A can opening device comprising, in combination, a frame adapted to be mounted on a stationary member, a can positioning and guiding member pivotally mounted near one of its ends in said frame, said member at its pivoted end having projecting means for engaging a can to aid in holding the same against said member, a

can punching element pivotally mounted on said member eccentrically of the pivot of said member and having a piercing end, a stop carried by said member limiting rotation of said element in one direction relative to said member and positioned to arrest said element with its piercing end extending in the direction and lying approximately in the plane of said member, means urging said element against said stop, and an abutment on said frame adapted to be engaged by said element and to hold said element against rotation relative to said frame until near the end of the pivotal movement of said member toward said frame.

10. A can opening device comprising, in combination, a frame adapted to be mounted on a stationary member, a can positioning and guiding member pivotally mounted near one of its ends in said frame, said member at its pivoted end having projecting means for engaging a can to aid in holding the same against said member, a can punching element pivotally mounted on said member eccentrically of the pivot of said member and having a piercing end, a stop carried by said member limiting rotation of said element in one direction relative to said member and positioned to arrest said element with its piercing end extending in the direction and lying approximately in the plane of said member, means urging said element against said stop, and a pivotal abutment on said frame adapted to be engaged by said element and to hold said element against rotation relative to said frame until near the end of the pivotal movement of said member toward said frame and to pivot and permit passing of said element in the opposite direction.
